CLAIM

The ornamental design for a golf tool, as shown and described.

DESCRIPTION

FIG. 1 is a perspective view of an embodiment of a golf tool in accordance with the present invention, shown in a closed position;

FIG. 2 is a top view of the golf tool of FIG. 1 in the closed position;

FIG. 3 is a side view of the golf tool of FIGS. 1 and 2 in the closed position;

FIG. 4 is an opposite side view of the golf tool of FIGS. 1-3 in the closed position;

FIG. 5 is a bottom view of the golf tool of FIGS. 1-4 in the closed position;

FIG. 6 is a front view of the golf tool of FIGS. 1-5 in the closed position;

FIG. 7 is a rear view of the golf tool of FIGS. 1-6 in the closed position;

FIG. 8 is a perspective view of the golf tool of FIGS. 1-7 in an open position;

FIG. 9 is a top view of the golf tool of FIGS. 1-8 in the open position;

FIG. 10 is a side view of the golf tool of FIGS. 1-9 in the open position;

FIG. 11 is an opposite side view of the golf tool of FIGS. 1-10 in the open position;

FIG. 12 is a bottom view of the golf tool of FIGS. 1-11 in the open position;

FIG. 13 is a front view of the golf tool of FIGS. 1-12 in the open position;

FIG. 14 is a rear view of the golf tool of FIGS. 1-13 in the open position; and,

FIG. 15 is a perspective view of the golf tool of FIGS. 1-14 in the closed position with an accessory portion extended. The broken lines illustrate unclaimed elements and are for illustrative purposes only; the broken lines form no part of the claimed design.

1 Claim, 15 Drawing Sheets
